UNITED STATES PATENT OFFICE

ALEX PETROW, OF SAN FRANCISCO, CALIFORNIA

REVERSIBLE AIRPLANE PROPELLER

Application filed April 10, 1929. Serial No. 354,006.

My invention relates to improvements in reversible airplane propellers, and it consists in the combinations, constructions and arrangements hereinafter described and 5 claimed.

An object of my invention is to provide a reversible airplane propeller that may be controlled from the cockpit of an airplane while the propeller is rotating. The mechanism for swinging the blades into different 10 angles is self-locking so as to hold the blades against accidental movement after they have been swung into the desired position. The power for changing the angles of the blades 15 is derived from the rotating propeller shaft.

A further object of my invention is to provide an indicating mechanism which will show at what angle the blades are positioned. The indicator functions while the propeller 20 is rotating.

Other objects and advantages will appear as the specification proceeds, and the novel features of the invention will be particularly pointed out in the appended claims.

25 My invention is illustrated in the accompanying drawing, in which

Figure 1 is a perspective view of the entire mechanism;

Figure 2 is a section along the line 2—2 of 30 Figure 3;

Figure 3 is a section along the line 3—3 of Figure 2;

Figure 4 is a section along the line 4—4 of Figure 2;

35 Figure 5 is a section along the line 5—5 of Figure 6;

Figure 6 is a top plan view of Figure 5; and

Figure 7 is a view showing a part of the indicating mechanism.

40 In carrying out my invention I make use of an engine crank shaft 1 (see Figure 3) that is rotated by an engine (not shown). The end of the shaft 1 has a square portion 2 and a threaded portion 3. A bullet-shaped casing or shell 4 has a square opening 5 for receiving the portion 2. The casing or shell 4 has a flange 6 that rides in a guide 7, the guide being secured to the airplane structure 8 by means of screws 9 or other suitable fastening means. A cap screw 10 is threaded

into the portion 3 and aids in locking the shell 4 against longitudinal movement. It will be seen from this construction that a rotation of the shaft 1 will rotate the shell 4.

45 Airplane blades 11 have suitable shafts 12 that are journaled in the shell 4. In the present drawing I have shown two blades. It is obvious that the number of blades may be increased if desired. The mechanism for turning each blade is identical, and therefore a description of one will suffice.

The upper blade 11 in Figure 2 carries a worm gear 13. A worm 14 meshes with the gear 13 and is mounted upon a shaft 15 that also carries a bevel gear 16. The gear 16 60 meshes with a gear 17, and this latter gear is carried by a suitable shaft 18. A toothed wheel 19 is carried by the shaft 18 and is shown meshing with a large wheel 20 that has a ring of small openings 21 for receiving 65 the teeth of the wheel 19.

The large wheel 20 is connected by a sleeve 21 with a second large wheel 22 of similar design. Reference to Figure 3 shows that the sleeve 21 is slidably mounted upon the shaft 70 1 and is held from rotation by guide pins 23 that in turn are carried by a bearing 24.

The large wheels 20 and 22 are held in neutral position with respect to the toothed wheels 19 by springs 25 and 26. In Figures 75 2 and 3 I have shown the wheels 20 and 22 moved to the right so as to mesh the wheel 20 with the toothed wheel 19.

The mechanism for moving the wheels 20 and 22 is shown in Figures 1, 2 and 3. Bars 85 27 are secured to the wheel 22, and these are slidably received in grooves 28 in the bearing 24. A lever 29 (see Figure 3) is fulcrumed at 30 and has a forked end 31 the arms of which have slots 32 for receiving 90 pins 33 carried by the bars 27.

In Figure 1, I show the outer end of the lever 29 as being connected to a push-and-pull rod 34, and I further show the rod as being operatively connected to a hand lever 95 35 placed in the cockpit of the airplane. A simple movement of the lever 35 forwardly, as shown in Figure 1, will cause the wheel 20 to engage with the toothed wheels 19. A reverse movement of the lever 35 will 100

bring the wheel 22 into engagement with the wheels 19.

I provide means for indicating the angle of the blades. A cam 36 is formed in the stub shaft 12 and will move a spring-pressed pin 37 (see Figure 2). The pin has an outwardly-turned portion 38 that will wipe through a grooved member 39 of the shape shown in Figures 5 and 6. The portion 38 will move through the member 39 in the direction of the arrow *a* shown in Figure 6.

The member 39 is mounted upon a shaft 40 (see Figure 3) that is connected to a link 41 by means of an arm 42 (see Figure 1). The connection between the link 41 and an indicator 43 is shown in Figures 1 and 7. The indicator 43 has a vertical shaft 44 that carries an arm 45 which is connected to the link 41.

The broken lines 46 and 47 show the two extreme paths through which the projection 38 moves. Figures 7 further shows how the member 39 is swung by the portion 38 as the portion passes between the upturned sides 48 of the member 39.

25 From the foregoing description of the various parts of the device, the operation thereof may be readily understood.

I have already set forth how the blades 11 may be swung into different angles by merely 30 actuating the hand lever 35. The worms 14 lock the blades in adjusted position and prevent further movement until either the wheel 20 or the wheel 22 is brought into mesh with the wheels 19. The spring-pressed pin 37 is 35 carried around with the shell 4 and is moved into different positions by the cam 36. The portion 38 will wipe through the member 39 for each revolution of the shell 4. This portion will swing the member 39 into a path that 40 will permit the portion 38 to pass through the slot 49 formed by the ends of the sides 48 disposed nearest each other. The bearings supporting the member 39 and the shaft 40 provide enough friction to hold the portion in 45 adjusted position. The movement of the member 39 will be dependent upon the angle of the blades 11, and this movement will be imparted to a needle 50 in the indicator 43 (see Figure 7), and this needle will move over a 50 scale that will indicate the angle of the blades. In this way the pilot will know the position of the blades while the propeller is functioning.

Although I have shown and described one 55 embodiment of my invention, it is to be understood that the same is susceptible of various changes, and I reserve the right to employ such changes as may come within the scope of the invention as claimed.

60 I claim:

1. A reversible airplane propeller comprising a rotatable shaft, airplane blades secured to said shaft so as to rotate therewith, said blades being rotatable into different angles, self-locking means for swinging the blades

into the desired angle and including a toothed wheel for each blade, and non-rotatable wheels movable into operative engagement with the toothed wheels, said toothed wheels being rotated by the stationary wheels thereby 70 swinging the blades in either direction into the desired angle.

2. A reversible airplane propeller comprising a rotatable shaft, airplane blades secured to said shaft so as to rotate therewith, said 75 blades being rotatable into different angles, self-locking means for swinging the blades into the desired angle and including a toothed wheel for each blade, a non-rotatable wheel movable into operative engagement with the 80 toothed wheels, said toothed wheels being rotated by the stationary wheel thereby swinging the blades into the desired angle, and a second non-rotatable wheel movable into operative engagement with said toothed wheels 85 for causing the latter to rotate in an opposite direction.

3. A reversible airplane propeller comprising a rotating shaft, a shell carried by said shaft and being rotated therewith, radially-extending propeller blades rotatably carried by said shell, self-locking means carried by said shell for rotating said blades in either direction, and manually-controlled means for operatively connecting said blade-rotating 95 means with the shaft for swinging the blades into the desired angles.

4. A reversible airplane propeller comprising a rotating shaft, a shell carried thereby and rotatable therewith, blades carried by 100 said shell and extending radially from the shaft, means for swinging said blades about their longitudinal axes, said means including a toothed wheel for each blade, and non-rotatable wheels slidably mounted on said shaft 105 and being movable into operative engagement with said wheels.

5. A reversible airplane propeller comprising a rotating shaft, a shell carried thereby and rotatable, therewith, blades carried by 110 said shell and extending radially from the shaft, means for swinging said blades about their longitudinal axes, said means including a toothed wheel for each blade, non-rotatable wheels slidably mounted on said shaft and being movable into operative engagement with said wheels, and spring means for urging 115 said non-rotatable wheels into neutral position.

6. A reversible airplane propeller comprising a rotating shaft, a shell carried thereby and rotatable therewith, blades carried by 120 said shell and extending radially from the shaft, means for swinging said blades about their longitudinal axes, said means including a toothed wheel for each blade, non-rotatable wheels slidably mounted on said shaft and being movable into operative engagement with said wheels, spring means for urging 125 said non-rotatable wheels into neutral position, 130

and an indicating means for showing the angle of the blades.

7. A reversible airplane propeller comprising a rotating shaft, a shell carried thereby and rotatable therewith, blades carried by said shell and extending radially from the shaft, means for swinging said blades about their longitudinal axes, said means including a toothed wheel for each blade, non-rotatable wheels slidably mounted on said shaft and being movable into operative engagement with said wheels, spring means for urging said non-rotatable wheels into neutral position, an indicating means for showing the angle of the blades, said indicating means comprising a cam on one of the propellers, a spring-pressed finger riding on the cam, a member swingable by the varying positions occupied by the finger, and an indicating pointer operatively connected to said member for indicating the angle of the blades.

8. A variable pitch propeller comprising a shaft, a shell rotatable therewith, a plurality of blades rotatably carried by the shell, a gear carried by each blade, a worm meshing with each gear, a pinion operatively connected with each worm, a pair of gears slidable on the shaft and held against rotation, said pair of gears normally straddling said pinions, springs for yieldingly holding said gears out of mesh with said pinions, and manually controlled means for moving either of said pair of gears into mesh with the pinions for swinging the blades into the desired angle.

9. A variable pitch propeller comprising a shaft, a shell rotatable therewith, a plurality of blades rotatably carried by the shell, a gear carried by each blade, a worm meshing with each gear, a pinion operatively connected with each worm, a pair of gears slidable on the shaft and held against rotation, said pair of gears normally straddling said pinions, springs for yieldingly holding said gears out of mesh with said pinions, normally controlled means for moving either of said pair of gears into mesh with the pinions for swinging the blades into the desired angle, and an indicating means for showing the angle of the blades.

10. A reversible airplane propeller comprising a rotating shaft, a shell carried by said shaft and being rotated therewith, radially-extending propeller blades rotatably carried by said shell, self-locking means carried by said shell for rotating said blades in either direction, manually-controlled means for operatively connecting said blade-rotating means with the shaft for swinging the blades into the desired angles, and an indicating means for showing the angle of the blades.

ALEX PETROW.
